OIL BURNER

Eugene Peters, South Orange, N. J., assignor to Metal-master Corporation, Newark, N. J., a corporation of New Jersey

Application May 27, 1955, Serial No. 36,265

Term of patent 3½ years

(Cl. D81—2)

Fig. 1 is a perspective view of an oil burner embodying my new design.

Fig. 2 is an elevational view thereof, on a reduced scale, taken at line 2—2 of Fig. 1, and

Fig. 3 is a side elevational view thereof, taken on line 3—3 of Fig. 2.

I claim:

The ornamental design for an oil burner, as shown.
